UNITED STATES PATENT OFFICE.

MICHAEL FITZGERALD, OF MEDINA, NEW YORK, ASSIGNOR OF ONE-THIRD TO JAMES H. CONLEY AND ONE-THIRD TO GEORGE R. CONLEY, BOTH OF MEDINA, NEW YORK.

STREET-INDICATOR.

1,257,208.

Specification of Letters Patent. Patented Feb. 19, 1918.

Application filed February 21, 1917. Serial No. 150,124.

To all whom it may concern:

Be it known that I, MICHAEL FITZGERALD, a citizen of the United States, residing at Medina, in the county of Orleans and State 5 of New York, have invented new and useful Improvements in Street-Indicators, of which the following is a specification.

This invention comprehends improvements in street indicators and relates more particularly to improvements in that type of 10 indicators disclosed in my application, Serial Number 81,940, allowed August 3, 1916, and issued as Patent 1,217,737.

One of the objects of the invention is to 15 provide an indicator having a web movable past a sight opening and carrying the names of streets or stations, means for advancing the web at each operation of the machine sufficiently far to project a name into registration with the sight opening and to positively lock the web when the name is so positioned.

Another object of the invention is to provide a bell sounding mechanism which will 20 operate to sound a bell each time the web is moved to disclose a new name.

The invention also aims to generally refine 25 and improve street and station indicators to render them more practical, useful and commercially desirable.

With these and other objects in view as will become more apparent as the description proceeds, the invention consists in certain novel features of construction, combination and arrangement of parts as will be hereinafter fully described, illustrated and claimed.

In the drawings,

Figure 1 is a front elevation of the street 40 indicator.

Fig. 2 is an end elevation of the indicator.

Fig. 3 is an elevation of the same end shown in Fig. 2 with the supplementary casing removed.

Fig. 4 is a fragmentary rear elevation with the rear casing wall removed, showing one end of the indicator.

Fig. 5 is a section on the plane of line 5—5 of Fig. 4.

Fig. 6 is a section on the plane of line 6—6 of Fig. 5.

Fig. 7 is a transverse vertical sectional view through the center of the indicator, and

Fig. 8 is a detail view partly in section

showing the braking means for one of the drum shafts.

Referring in detail to the drawings by numerals, 1 designates, as an entirety, a casing having a front wall 2 formed with a centrally disposed sight opening 3 and carrying above this opening, a hood or reflector 4 in which may be positioned a light 5 to illuminate the signal opposite the sight opening.

Shafts 6 and 7 extend longitudinally through the casing above and below the sight opening and carry drums 8 around which a web 9 carrying transversely disposed and equally spaced indicating names 70 of streets or stations is wound. The shafts extend through the casing wall 10 and each of them has fixed on its extended portion a ratchet wheel 11. Yoke levers 12 and 13 are loosely mounted on the shafts with their 75 arms extending on opposite sides of the ratchet wheels. These yoke levers converge rearwardly toward each other and are provided adjacent their overlapping ends with longitudinal slots 14 through which a pin 80 15 extends. This pin has an enlarged head movable in the guide 16 and carries a bail or clevis 17 which is connected to one end of a pull cord 18. Springs 19 return the levers to their rear positions after having been 85 actuated by their cord 18. Each of the levers is provided with a spring pressed pawl 20 adapted to engage its ratchet wheel 11. To hold the pawls from engagement with the ratchet wheels, I provide releasing 90 plates 21 pivotally mounted and each having a marginal recess 22 to receive the pawl arm 23 and hold the pawl in inoperative position. The releasing plates are each provided with a handle 24 which extends laterally through 95 a slot 25 in the wall 26 of the supplementary casing 27.

To stop the web at each operation of the machine after it has moved a fixed distance, I provide a stop roller journaled in the sides 100 of the casing in line with the sight opening. This roller is formed with teeth or spurs 29 which work in openings or eyelets 30 formed in the web adjacent one edge thereof. The roller is formed with radial sockets 31 preferably four in number to receive a stop means. Mounted upon the wall 10 of the casing is a pair of ratchet levers 32 which are pivoted intermediate their ends. Each of the ratchet levers is provided on one end 110

with a tooth 33 adapted to engage a ratchet wheel 34 on the corresponding drum 8; and on its other end with a tooth or extension 35 adapted to seat in one of the sockets 31 and 5 hold the roller against rotation. An outwardly extending arm 36 is carried by each of the levers 32 adjacent its outer end and extends through an opening 37 in the casing wall. Each of the levers is normally held 10 out of engagement with the ratchet wheels 34 by an arm 28 which bears against a collar 39 on the lever arm 36. The angular arms 38 are carried by the yoke levers 12 and when the levers are in position shown in 15 Fig. 3, they hold the levers 32 inoperative against the tension of the springs 40.

To sound bell 41 at each operation of the machine, I provide a lever 42 pivotally mounted at its upper end and having an outwardly extending arm 43 which extends through the slot 44 to strike the bell hammer 45. A spring 46 urges the lever 42 toward the bell hammer. A bolt 47 is pivoted to the lever 42, works through guides 48 and is 20 adapted to project into one of the sockets 31.

In Fig. 8 is shown the means for braking the drum shafts. 49 designates a bearing having a hollow extension 50 in which is mounted a shoe 51 pressed into engagement 30 with the shaft by a spring 52 which bears at its outer end against a plug 53. This arrangement is provided on one end of each of the drum shafts 6 and 7.

In the operation of the indicator, one of 35 the pawls 20 is first thrown out of operation and also the corresponding ratchet lever 32. This latter member is held inoperative by one of the pivoted plates 54 on the supplementary casing 27, as shown in 40 Fig. 2. Now with the parts arranged as shown in the drawings, a pull on the cord 18 will swing the levers 12 and 13 and rotate the upper drum to wind the web thereon. As the yoke lever 12 moves forwardly, the 45 arm 38 attached thereto, travels rearwardly allowing the tooth 35 of the upper ratchet lever 32 to bear against the periphery of the stop roller 28. When the web has traveled sufficiently far to bring one of the sockets 50 31 in the path of the tooth 35, said tooth will seat in the socket and lock the roller, thus stopping the movement of the web. As the tooth 35 snaps into the socket 31, the tooth 33 on the other end of the lever 32 55 will engage the ratchet wheel 34 of the upper drum and lock the same, thus completing one operation of the device. As the yoke lever 13 moves forwardly, it allows the lever 42 to swing rearwardly under the 60 tension of its spring 46 to bring the end of the bolt 47 against the periphery of the roller 28. When one of the sockets 31 comes into alinement with the bolt, the latter snaps thereinto, allowing the lever 65 arm 43 to strike the bell hammer a quick

blow. When desired, the direction of travel of the web may be reversed by releasing the lower pawl 20 and lever 32 and locking the upper pawl and lever.

From the foregoing description taken in 70 connection with the accompanying drawings, it will be apparent that I have provided a very practical street indicator having a movable web which is locked against further movement after having traveled a 75 fixed distance on the operation of the machine.

While I have shown and described the preferred embodiment of my invention, it will be clearly understood, that I do not 80 wish to be limited to this construction, but may make such changes as will fall within the scope and spirit of the invention as claimed.

What I claim is:—

85

1. In an indicator of the character described, a pair of drums, a web connected to and windable on said drums, means for driving one of said drums to wind the web thereon, a roller having teeth working 90 through openings in the web, and a lever controlled by the roller to lock the driven drum after it has moved the web a fixed distance.

2. In an indicator, a casing having a 95 sight opening therein, a pair of drums, a web connected to said drums and windable thereon past the sight opening, means for driving one of the drums to wind the web thereon, a roller operated by the web, a 100 ratchet wheel on the driven drum and a lever controlled by the roller to lock the driven drum after it has advanced the web a fixed distance.

3. In a street indicator, a casing having 105 a sight opening therein, a pair of drums, a web connected to said drums and windable thereon past the sight opening, means for selectively driving the drums, a roller operated by the web, and selective means controlled by the roller for stopping the driven drum after it has moved the web a predetermined distance.

4. In an indicator of the character described, a casing having a sight opening, a 115 pair of drums, a web connected to said drums and windable thereon, means for selectively driving the drums, a ratchet wheel on each of the drums, a ratchet lever for each drum to lockingly engage the ratchet 120 wheel thereof, a roller being formed with radial sockets, teeth on the ratchet levers to seat in said sockets and allow the ratchet levers to lockingly engage their ratchet wheels and means for holding one of the 125 ratchet levers inactive, the other ratchet lever operating to lock the driven drum after it has advanced the web a predetermined distance.

5. In an indicator of the character de- 130

- scribed, a casing having a sight opening therein, a pair of drums, a web connected to and windable on said drums past the sight opening, means for selectively driving the 5 drums, a roller positively driven by the web, and locking means controlled by the roller to stop the driven drum after the roller has been rotated a fixed distance by the web.
- 10 6. In an indicator of the character described, a casing having a sight opening, a pair of drums mounted within said casing, a web connected to said drums and windable thereon past the sight opening, means for 15 selectively driving the drums, a roller having teeth, the web being formed with openings through which said teeth project, locking means engaging the drums and controlled by the roller to lock the drums after the web has moved a predetermined distance, said locking means being disengaged from the drums by a return of the selective driving mechanism to starting position. 20
7. In an indicator of the character described, a web driven roller having radial 25 sockets, and bell sounding mechanism engageable in said sockets to ring a bell.
8. In an indicator of the character described, a web driven roller having radial sockets formed therein, a bell, a spring 30 pressed lever having an arm to sound said bell and a bolt seatable in said sockets to allow the lever to move into operative position.

In testimony whereof I affix my signature. 35
MICHAEL FITZGERALD.
